[57] CLAIM

The ornamental design for a shoe midsole, as shown and described.

DESCRIPTION

FIG. 1 is a top plan view of a shoe midsole showing our new design;

FIG. 2 is a side elevational view of one side of the shoe midsole shown in FIG. 1;

FIG. 3 is a side elevational view of the other side of the shoe midsole shown in FIG. 1;

FIG. 4 is a front elevational view of the shoe midsole shown in FIG. 1;

FIG. 5 is a rear elevational view of the shoe midsole shown in FIG. 1;

FIG. 6 is a cross section taken along line 6—6 of FIG. 1;

FIG. 7 is a cross section taken along line 7—7 of FIG. 1;

FIG. 8 is a cross section taken along line 8—8 of FIG. 1; and,

FIG. 9 is a cross section taken along line 9—9 of FIG. 1.

The broken lines showing the shoe upper and the remaining portions of the sole in FIGS. 2—5 are for illustrative purposes only and form no part of the claimed design.

FIG. 1

FIG. 6

FIG. 7

FIG. 8

FIG. 9
